UNITED STATES PATENT OFFICE.

MAX JANOFSKY, OF WASHINGTON, DISTRICT OF COLUMBIA, ASSIGNOR OF ONE-HALF
TO ISADORE SMALL, OF WASHINGTON, DISTRICT OF COLUMBIA.

BOTTLE CAPPER.

Application filed April 11, 1921. Serial No. 460,470.

To all whom it may concern:

Be it known that I, MAX JANOFSKY, a citizen of the United States, residing at Washington, in the District of Columbia, have invented certain new and useful Improvements in a Bottle Capper, of which the following is a specification.

This invention relates to bottle cappers, and particularly to portable hand operated devices for applying caps to bottles so as to 10 hermetically seal the latter.

An object of the invention is to provide a capping device for use in applying bottle crowns, which is of simple construction and 15 easy operation; which has its parts so arranged that the gripping action of the hand will be amply sufficient to firmly apply the crown to the bottle; which requires no pressure mechanism or means for holding the 20 bottle during the capping operation; which is adaptable to bottles having necks of various formations; which is equipped with means for preventing such pressure being applied in the crowning operation as would 25 injure the cap or break the bottle neck; and which may be readily applied to and removed from the bottle neck.

A still further object of the invention is to provide a bottle capper which is of such construction and formation as to enable the same to be manufactured and marketed at 30 low cost which requires the exercise of no special skill or "knack" to operate the same, and which will prove thoroughly practical 35 and efficient in use.

With these objects in view together with others which will appear as the description proceeds, the invention resides in the novel construction, combination and arrangement 40 of parts, all as will be described more fully hereinafter, illustrated in the drawing, and particularly pointed out in the claim.

In the drawing:

Figure 1 is a vertical sectional view taken 45 through the improved bottle capper and illustrating, diagrammatically, the application of the capper to a bottle of conventional construction.

Figure 2 is a front illustration of the 50 capper, and

Figure 3 is an enlarged horizontal sectional view taken through the capper and looking downwardly.

More particularly, the capper comprises 55 a holding member indicated at 4 which may

be formed of suitable metal, cast or otherwise, and this holding member is preferably provided at its lower end with spaced parallel arms 5 to accommodate the capper head to be hereafter described and to assist in holding the capper properly positioned upon the bottle. In the present instance the arms 5 are spaced apart a distance somewhat greater than the diameter of the bottle neck, and the said arms, being parallel with the holding member 4, are connected at their lower ends by the plate 6. This plate is provided in its forward edge with a notch recess indicated at 7, to receive the neck of the bottle to which the device is to be applied. The notch 7 is of such size as to enclose the bottle neck below the bead thereon, and the edges of the notch engage beneath the lower bead on the bottle so as to prevent movement of the said plate in an outward direction beyond the bead.

The standard 4 is provided in its forward face with a channel to slidably receive a plunger 8. The plunger, in the present instance, is rectangular in cross section, and slides within the groove defined by the forwardly projecting spaced ribs 9 of the holding member. The channel upon the holding member is so arranged that the plunger 8 will be properly aligned with the central portion of the notch 7 of the plate 6.

The lower end of the plunger is provided with a capping head indicated at 10, the said head including an annular projecting flange 11 of a diameter slightly less than the crimped edge of the ordinary bottle crown.

The forward face of the plunger 8 is provided with teeth 12 which are in mesh with the segment 13 pivoted as at 14 between the spaced arms 15 on the standard. This segment is provided with a lever 16 which extends in an outward direction, and the lever is limited in its movement in one direction by the grip 17 formed at the upper end of the standard 4.

In operating the device, the neck of the bottle is inserted in the notch 7 of plate 6 so that the edges of the said notch are disposed below the lower bead on the bottle neck. The lever 16 is moved forwardly or away from the grip 17, whereupon the plunger 8 will be raised. The crown may be placed upon the bottle neck or may be pressed into the lower end of the head 10.

The lever 16 is then grasped by the hand and moved inwardly or toward the standard. The lever and grip are so arranged as to be conveniently grasped by the hand, and the clutching action of the latter will cause the lever to force the plunger down and firmly engage the crown with the neck of the bottle. The segment 13 and lever 16 are so proportioned that the application of ordinary gripping pressure will be sufficient to apply the cap to the bottle and to force the crimped edge of the cap around the upper neck bead so as to hermetically seal the bottle. It will be understood, of course, that the annular depending flange 11 of the capper head will be of slightly smaller diameter than the outer edges of the crimps on the bottle crown, whereupon movement of the head to its lowest position will cause this crimped edge to be bent inwardly so as to tightly grip the bottle bead.

The grip 17 acting as a stop for lever 16, is arranged at such inclination that the movement of the lever will be arrested after the capper head has moved downwardly a distance sufficient to apply the crown to the ordinary type of crown seal bottle. Should it happen that the device is to be used with bottles having a deeper lower bead than that shown in the present instance, it will be necessary to make a slight adjustment in the movement of the plunger 8. This may be easily accomplished by withdrawing the pivot pin 14 and moving or removing segment 13. The plunger 8 may then be moved

upwardly a slight distance before the segment is reinserted in position between the arms 15, as will be readily understood.

While the above is a description of the preferred embodiment of the invention it will be understood that variation in the details and arrangement of parts may be resorted to without departing from the invention as defined by the claim.

Having thus described my invention, what I claim is:—

In a device of the character described, a vertical holding member, the upper end of which is bent to form a stop and hand grip, and further provided with two spaced longitudinal ribs arranged to form a channel, spaced arms extending from said ribs, said arms being arranged to accommodate a removable pin, the lower end of said holding member being formed with spaced parallel arms terminating in a bottle supporting collar extending substantially at right angles to said arms, a rack movable in said channel, terminating at its lower end in a capping die, and an operating lever pivoted on said removable pin, having integral therewith a gear segment adapted to mesh with said rack, said lever being movable in the capping operation toward said hand grip, whereby said lever and hand grip may be grasped by a hand of the operator.

In testimony whereof, I affix my signature.

MAX JANOFSKY.
